UNITED STATES PATENT OFFICE.

ADA COLEMAN AND ISADORE A. COLEMAN, OF BALTIMORE, MARYLAND.

ADJUSTABLE BOOK COVER.

Application filed May 20, 1925. Serial No. 31,492.

To all whom it may concern:

Be it known that we, ADA COLEMAN and ISADORE A. COLEMAN, citizens of the United States, residing at Baltimore, in the State of Maryland, have invented certain new and useful Improvements in Adjustable Book Covers, of which the following is a specification.

This invention relates to improvements in adjustable book covers, and has for its object to provide a simple, cheap and efficient cover which can be readily adjusted to any size book and quickly secured in position thereon, and which can also be readily removed when desired.

The invention consists of the novel construction and arrangement of the parts and combination of parts hereinafter more fully set forth in the following specification and pointed out in detail in the appended claims.

In the accompanying drawing,—

Figure 1 is a plan view of the leaves and one side of the book back in vertical position and the other side of the back down and the cover folded over it and secured by the fastener.

Figure 2 is a section on the line 2—2 of Figure 1.

Referring to the accompanying drawing, forming part of this specification, and in which like reference numerals designate like parts throughout the several views thereof, 1 designates the sides of the cover which are provided with the tabs 2 and 3, having a number of holes 4 and 5, respectively, to receive the fasteners 6. The apertures 4 of the tabs 2 on each of the sides 1 are in alignment with each other and the apertures 5 of the tabs 3 are at right angles to the apertures 4 of the tabs 2, so that when the tabs 2 and 3 are folded over each other the apertures 4 and 5 will be brought in vertical alignment at a point where the apertures 5 cross the apertures 4, so that the fastener 6 can be inserted through the apertures 4 and 5 at this point to hold the cover in the adjusted position on the book. The two sides 1 each has its edge between the tabs 2, 2 folded back as at 7, and upon the said folded edges 7 is a piece 8, stitched for a portion of its length at 9, leaving the ends thereof free to be folded back to ac-

commodate the length of the back 10 of the book. This folded edge 7 provides a double edge when the cover is folded and prevents any raw edges from being exposed at this point when the cover is folded over the back of the book. The sides 1 are each provided with apertures 11 near the tabs 3 and have a preliminary or primary fold the flap of 60 which is held in the partly folded condition of the cover by a fastener 12 so that when the cover is folded over the back of the book the sides will be folded in to prevent any raw edges from being exposed. 65

Having thus described our invention, what we claim is:

1. An adjustable book cover comprising two sides formed of flexible material and each having its inner edge folded over and 70 a tab at each end of said folded edge and a tab on the edge opposite the folded edge and each of said tabs being provided with a row of apertures adapted to be brought into vertical alignment when the said tabs are 75 folded over each other, and a flexible piece secured to both of said folded edges and having its ends free to be folded back to accommodate books of various lengths.

2. An adjustable book cover comprising 80 two sides formed of flexible material and each having one edge folded and stitched down for a portion of its length and a tab extending beyond each end of the folded edge, and a tab on the side opposite the 85 folded edge, each of said tabs being provided with a row of apertures adapted to be brought into vertical alignment when the said tabs are folded over each other, a flexible piece secured to both of said folded 90 edges and having its ends free to be folded back to accommodate the various sizes of books.

3. An adjustable book cover comprising 95 two sides formed of flexible material and each having one edge folded and stitched down for part of its length, and a tab extending beyond each end of the folded edge and provided with a row of apertures, and a tab on the edge opposite the folded edge 100 each provided with a row of apertures at right angles to the apertures of the first named tabs, apertures in each side of the cover and on opposite sides of the last named

2
tabs, preliminary folds on opposite edges of each of said sides, fasteners passing through said last named apertures to hold the flap of said preliminary folds, a flexible piece secured to both of the folded and stitched edges and having its outer end free to be folded back to accommodate the various sizes

of books, and a fastener to hold the sides in the completely folded position when on the book.

10

In testimony whereof we affix our signatures.

ADA COLEMAN.
ISADORE A. COLEMAN.
